UNITED STATES PATENT OFFICE.

GEORGE BINET DOREY, OF MONTREAL, QUEBEC, CANADA.

FRICITION DRAFT RIGGING.

Application filed August 22, 1921. Serial No. 494,192.

To all whom it may concern:

Be it known that I, GEORGE BINET DOREY, a subject of the King of Great Britain, and residing in the city of Montreal, Province 5 of Quebec, Dominion of Canada, have invented certain new and useful Improvements in Friction Draft Riggings, and do hereby declare the following to be a full, clear, and exact description of the same.

10 My invention relates to improvements in friction draft riggings for railway cars and the like, and is especially related to that class of draft riggings wherein wedging elements are used in connection with casings 15 and friction members to create frictional resistance and augment the cushioning power of the device. In gears of the identified type it is common practice to have wedging members re-act with great force transversely 20 of the casing thereby tending to split this member.

It is therefore an object of the present invention to partially relieve the casing of this excessive strain by loosely mounting an 25 auxiliary movable cage which will function as a wedge retaining member and take a portion of this transverse strain thereby permitting the main casing to more properly exercise its main function as a column member.

30 Another object of the present invention is to improve the construction of draft riggings whereby pressure transmitting members having a comparatively short travel 35 and moving at a low velocity will displace friction resistance members a greater distance and at a greater velocity.

A main object of the invention is to provide novel means for utilizing a definite portion 40 of the energy used in compressing the draft gear as a means of increasing the resistant power of resistant members.

45 A further object of the invention is to provide a friction draft rigging which will be certain to release after compression. A difficulty hitherto experienced in gears of high capacity has been the liability of the wedging elements binding against the casing walls and so preventing the gear from 50 returning to the normal release position.

Further my invention consists in certain novelties of design and construction of parts which will be more particularly pointed out in the annexed specification and claims.

55 The accompanying drawings illustrate an example of the physical embodiment of the

invention as applied between the sills of a railway car.

Figure 1. is a longitudinal horizontal sectional view through the complete gear as assembled, the parts being in the normal or extended position.

Figure 2. is a view similar to Figure 1. showing the gear in the fully compressed position.

Figure 3. is a sectional view taken through the gear on line 3—3.

Figure 4. is a perspective view of the outer casing.

Figure 5. is a perspective view of one of 70 the friction shoes.

Figure 6. is a perspective view of the inner frictional resistance member.

Figure 7. is a perspective view of the inner 75 casing or wedge retaining cage.

Figures 8 and 9 are perspective views of the wedge pressure blocks known as pressure transmitting members.

In the drawings 2 represents the drawbar of the coupler connected by means of key 3 80 to the yoke 4 in the usual member, the yoke embracing the casing 5 and the whole being located between the center sills 6 and 7. In the illustrations the casing is formed to abut against front stops 10 and 11 which are secured to the center sills, rear stops 8 and 9 also secured to the center sills constitute draft gear abutments under buffing strains.

The outer casing 5 is preferably formed of rectangular shape with one end closed and 90 the other end open and is formed with two oppositely beveled faces 12 on the walls at some distance from the open end of the casing. The upper portion of these walls are preferably made straight as at 5^a and constitute guides between which the wedge retaining cage 13 moves and is thereby secured from undue sidewise movement. The outside walls 13^a of the cage 13 are also made straight to slide between the walls 5^a of the 100 casing 5. The inner walls of the cage 13 are beveled in opposite directions as at 14 and 15. Top and bottom walls 13^b securely tie the two portions of the wedge retaining cage. The beveled portions of the cage at 14 are 105 opposed to those at 12 of the casing 5 and interposed between these members are wedge friction shoes 16 which have beveled surfaces 17 and 18 formed to register with the corresponding beveled surfaces on the cage 110 13 and on the casing 5. The inner walls of the shoes as at 19 are then parallel and be-

- tween these parallel walls a friction member 20 is mounted and is adapted to have reciprocatory motion between and in engagement with these shoes. The side walls 21 of this friction member constituting friction surfaces against which the friction walls 19 of the friction shoes 16 are forced when the inner cage and outer casing are moved towards each other.
- 10 The central friction member 20 has its front surface formed in the shape of a wedge by means of front walls 22 which are angularly disposed relatively to each other. This surface 22 together with surface 15 of the cage 13 form a wedge shaped recess on each side of the center of the draft rigging within which the wedge block pressure transmitting members 23 and 24 operate. The wedge block pressure transmitting members 23 and 24 are disposed on each side of the longitudinal center of the draft rigging and are each formed with bearing surface 23^a and 24^a constituting one face of a wedge which register with surfaces 15 of the cage 13. The adjacent surfaces of these pressure transmitting members as at 23^b and 24^b register with surfaces 22 of the central friction member 20. On the draft rigging being compressed the pressure transmitting members 23 and 24 are forced into the outer casing and by reason of their bearing on the inclined walls of the cage they are also caused to move transversely towards each other.
- 15 30 35 40 45 50 55 60 65 70 75 80 85 90 95 100 105 110 115 120 125 130
- Interposed between the wedge block pressure transmitting members 23 and 24 and the rear stops is a follower plate 25. As the wedge blocks move transversely of the draft rigging the faces 23^c and 24^c of these members co-acting with face 25^a of the follower 25 friction is created at these points.
- In order to stabilize the pressure transmitting members and prevent one from moving faster than the other these members have been formed with overlapping portions; for this purpose wedge block 23 has been fitted with a recess 23^d into which projection 24^d of wedge block 24 is adapted to move.
- Friction member 20 is hollowed out to receive outer spring 26 and inner spring 27 which are adapted to return the gear to normal release position after compression and to maintain all the parts in operative relation.
- The operation of the draft gear takes place as follows:—
- In draft or buffing strains the draft gear is compressed by the approach of follower 25 to casing 5, the rear follower abutting against rear stops 8 and 9. This movement causes wedge block pressure transmitting members 23 and 24 to be moved longitudinally into the casing 5 and owing to their bearing on the inclined surfaces 15 of the

wedge cage 13 there will also be transverse movement along face 25^a of the follower 25 thus creating considerable friction at these points. The inward longitudinal and inward transverse movement of the pressure transmitting members is strongly resisted by the central friction member 22 which has its upper surface formed in the form of an apex. By reason of the inclination of the upper walls of member 22 this member is forced a greater distance than the wedge pressure transmitting members inasmuch as the latter moving towards each other in a transverse direction create a squeezing action on the inclined walls of the former. During this action the outward force incidental to the transverse movement of the wedge blocks 23 and 24 is resolved into an inwardly acting force through the medium of the wedge cage, which having inclined walls 15 converts this outward reaction into a longitudinal thrust, which acting on surface 17 of the wedge shoes 16 through the medium of inclined wall 14 of the wedge cage again converts this force into a transverse one ending to press the friction shoes 16 against the friction member 22. In this manner the direction of the forces is reversed and a portion of the energy generated by the impact of the instrumentalities which it is desired to cushion will be utilized to increase the effectiveness of the resistant portion of the rigging. The ends of the shoes 16 as at 18, on the ends remote from the wedge cage, are also inclined and co-act with similarly inclined surfaces 12 of the casing 5 thereby providing a very stable mechanism inasmuch as the shoes are forced against the friction member from both ends.

The wedge pressure transmitting members are adapted to move with the follower in the same ratio as the coupler but displacing the friction member 22 a greater distance and at a greater velocity the advantage of great resistance with relatively small bearing pressures is secured thereby obviating the disadvantage of seizure between the friction members. As the friction member 22 is moved inwardly into the casing the outer spring 26 and inner spring 27 are compressed thereby.

On release of the mechanism the springs expand returning the friction member 22 in a forward direction which has the effect of moving the pressure transmitting members in an outward direction both transversely and longitudinally and at the same time moving the follower and coupler back to the normal release position.

The liability of the draft rigging binding and failing to release is entirely eliminated in this invention inasmuch as the entire friction mechanism as comprised by the follower, wedge pressure transmitting members, wedge cage, friction member, and fri-

tion shoes are only related to the casing through the medium of the flaring beveled walls as at 12 and in the event of these members being tightly wedged the entire mechanism comprised of the above parts will be moved bodily forward out of engagement with the casing. Such movement, however small, immediately breaks all the wedging engagement and the parts immediately resume their normal release position, the springs furnishing the necessary energy to return the gear to the release position and at the same time maintain all the parts in operative relation.

15 While I have shown and described with particularity only a single embodiment of my invention I do not desire to be limited to the exact structural details thus illustrated and described; but intend to cover all 20 forms and arrangements which come within the terms employed in the definitions of my invention constituting the appended claims.

What I claim is:

1. In a friction draft rigging, pressure 25 transmitting members having adjacent inclined surfaces, one of such surfaces being adapted to act upon and displace a friction member and the other of such surfaces being adapted to move friction shoes against the 30 friction member.

2. In a friction draft rigging, the combination with a drawbar having movement, pressure transmitting members having adjacent inclined surfaces, one of such surfaces 35 being adapted to act upon and displace a friction member a greater distance than the drawbar moves and the other of such surfaces being adapted to force friction shoes against the friction member.

40 3. In a friction draft rigging, a follower, pressure transmitting members having a surface movable along the face of such follower and two surfaces angularly disposed thereto, one of such surfaces being adapted 45 to act upon and displace a friction member and the other of such surfaces being adapted to move friction shoes against the friction member.

4. In a friction draft rigging for railway 50 cars, a friction member mounted for reciprocating motion between parallel faces of friction shoes, relatively approachable members having wedging engagement with the outer faces of the friction shoes, wedge pressure 55 transmitting members having adjacent surfaces, one of which is adapted to displace the friction member and the other of such surfaces being adapted to force the relatively approachable members together.

60 5. A friction draft rigging for railway cars comprising a friction member mounted for reciprocating motion between parallel faces of friction shoes, the said shoes having their ends wedge shaped and oppositely inclined; wedging means acting on each end

of such shoes for forcing them against the friction member and wedge pressure transmitting members adapted to operate the wedging means and move the friction member.

6. In a friction draft rigging the combination with a drawbar having movement of a friction member adapted to be displaced thereby a greater distance than the drawbar, the said friction member having reciprocating motion between parallel faces of friction shoes which have oppositely inclined wedge shaped ends and wedging means acting on each end of such shoes for forcing them against the friction member.

7. In a friction draft rigging the combination with a casing of friction shoes in wedging engagement therewith and a friction member in sliding engagement with the 85 shoes and wedge pressure transmitting members adapted to force the shoes against the friction member and move the latter relatively to the shoes.

8. In a friction draft rigging the combination with a central friction member of 90 casings having oppositely inclined walls, one of such casings being contained within the other and constituting a wedge retaining cage, wedge friction shoes interposed between the inclined walls of the casings and 95 the central friction member and wedge members co-acting with the inner casing to force the shoes against the friction member and move the latter relatively to the shoes, and springs for maintaining the parts in 100 operative relation.

9. In a friction draft rigging in combination a central friction member, friction shoes engaging the walls of such member, outer and inner casings having wedging engagement with the shoes at their outer ends and wedge pressure transmitting members having adjacent faces, one face being in wedging engagement with the inner casing and the other face in wedging engagement with 110 the central friction member and springs for yieldingly maintaining all the parts in operative relation.

10. In a draft rigging in combination an outer casing, an inner casing, shoes interposed therebetween and adapted to be forced inwardly axially to the line of draft on relative approach of the casings, a longitudinally movable central friction element resisting such movement and being movable 120 relatively to the shoes and springs for yieldingly maintaining the parts in operative relation.

11. In a friction draft rigging in combination a drawbar, a casing, a central friction member and friction shoes in engagement therewith, wedges adapted to move the friction member relatively to the shoes a greater distance than the drawbar and a loosely mounted wedge retaining cage in- 130

- terposed between the wedges and the shoes for the purpose of forcing the latter axially to the line of draft against the friction member.
- 5 12. In a friction draft rigging for railway cars the combination with a casing of pressure transmitting members adapted to displace a friction member, a cage supporting the pressure transmitting members, and 10 wedge shoes co-operating with the cage and the casing for retarding the pressure transmitting members through the medium of the friction member and springs for yieldingly maintaining the parts in operative relation.
- 15 13. In a friction draft rigging for railway cars the combination with a casing of pressure transmitting members having a transverse reaction of a loosely mounted 20 wedge retaining cage adapted to take the transverse thrust; the walls of the said casing constituting guides for the wedge cage.
- 25 14. In a friction draft rigging for railway cars wedge pressure transmitting members having longitudinal and transverse movement and wedging means co-operating therewith for converting the outward thrust incidental to such transverse movement into an inward force.
- 30 15. In a friction draft rigging for railway cars the combination with a drawbar and a casing of pressure transmitting members co-operating with the drawbar for forcing a friction member inwardly into the casing, the said pressure transmitting mem- 35 bers consisting of wedges each having a surface in engagement with the friction member and having the adjacent surface acting upon a member extending from one pressure transmitting member to the other 40 and constituting a wedge retaining cage, the said cage being adapted to force friction shoes into engagement with the aforementioned friction member and springs extending within this member for the purpose of maintaining the parts in operative relation. 45
16. In a friction draft rigging for railway cars the combination with outer and inner casings of a friction mechanism comprising inner and outer members, the outer members having their outer faces inclined and registering with similarly tapered faces on the walls of the casings, and the inner walls of such outer members being straight and disposed in the line of draft; the said outer members being adapted to be forced against the inner member on relative approach of the casings, and pressure transmitting members adapted to move the inner portion of the friction mechanism relatively 50 to the outer portion and springs for yieldingly maintaining the parts in operative relation. 55
- 55 In testimony whereof I have hereunto set my hand in the presence of two witnesses. 60 65
